(57) **CLAIM**

The ornamental design for a gemstone setting, as shown and described.

DESCRIPTION

FIG. 1 is a top view of a gemstone setting showing my new design;

FIG. 2 is a bottom view of the gemstone setting in FIG. 1; FIG. 3 is a top and front perspective view of the gemstone setting in FIG. 1;

FIG. 4 is a right side view of the gemstone setting in FIG. 1;

FIG. 5 is a left side view of the gemstone setting in FIG. 1; FIG. 6 is a rear view of the gemstone setting in FIG. 1; and, FIG. 7 is a front view of the gemstone setting in FIG. 1.

The broken lines in the drawings illustrate portions of the gemstone setting that form no part of the claimed design.
